US00D529967S

(12) **United States Design Patent** (10) Patent No.: **US D529,967 S**
Bowen et al. (45) Date of Patent: **** Oct. 10, 2006**

(54) **TOY VEHICLE AND PARTS THEREOF**

(75) Inventors: **David Bowen**, Hermosa Beach, CA (US); **Paulo Kang**, Pasadena, CA (US)

(73) Assignee: **Mattel, Inc.**, El Segundo, CA (US)

(**) Term: **14 Years**

(21) Appl. No.: **29/235,734**

(22) Filed: **Aug. 4, 2005**

CLAIM

The ornamental design for toy vehicle and parts thereof, as shown and described.

DESCRIPTION

FIG. 1 is a perspective view of a first configuration toy vehicle in accordance with our new design;
 FIG. 2 is a “front” elevation view thereof;
 FIG. 3 is a “rear” elevation view thereof;
 FIG. 4 is a “right” side elevation view thereof, the left side being a mirror image;
 FIG. 5 is a “top” plan view thereof;
 FIG. 6 is a “bottom” plan view thereof;
 FIG. 7 is a perspective view of a second configuration toy vehicle in accordance with our new design;
 FIG. 8 is a “front” elevation view thereof;
 FIG. 9 is a “rear” elevation view thereof;
 FIG. 10 is a “right” side elevation view thereof, the left side being a mirror image;
 FIG. 11 is a “top” plan view thereof;
 FIG. 12 is a “bottom” plan view thereof;
 FIG. 13 is a perspective view of a third configuration toy vehicle in accordance with our new design;

FIG. 14 is a “front” elevation view thereof;
 FIG. 15 is a “rear” elevation view thereof;
 FIG. 16 is a “right” side elevation view thereof, the left side being a mirror image;
 FIG. 17 is a “top” plan view thereof;
 FIG. 18 is a “bottom” plan view thereof;
 FIG. 19 is a perspective view of a fourth configuration toy vehicle in accordance with our new design;
 FIG. 20 is a “front” elevation view thereof;
 FIG. 21 is a “rear” elevation view thereof;
 FIG. 22 is a “right” side elevation view thereof, the left side being a mirror image;
 FIG. 23 is a “top” plan view thereof; and
 FIG. 24 is a “bottom” plan view thereof.
 FIG. 25 is a perspective view of a fifth configuration toy vehicle in accordance with our new design;
 FIG. 26 is a “front” elevation view thereof;
 FIG. 27 is a “rear” elevation view thereof;
 FIG. 28 is a “right” side elevation view thereof;
 FIG. 29 is a left side elevation view thereof;
 FIG. 30 is a “top” plan view thereof;
 FIG. 31 is a “bottom” plan view thereof;
 FIG. 32 is a perspective view of a sixth configuration toy vehicle in accordance with our new design;
 FIG. 33 is a “front” elevation view thereof;
 FIG. 34 is a “rear” elevation view thereof;
 FIG. 35 is a “right” side elevation view thereof, the left side view being a mirror image thereof;
 FIG. 36 is a “top” plan view thereof; and
 FIG. 37 is a “bottom” plan view thereof.
 The “vanes” forming the two “wheels” of the fifth configuration vehicle (FIGS. 25–31) could be reversed 180 degrees from the directions depicted in FIGS. 25–31 to provide a seventh configuration vehicle, the views of which would be mirror images of FIGS. 25–31. Any combination of the configurations 1–4 can be provided in one vehicle by making the vanes forming wheels of the vehicle and/or the “tail” extending “rearward” from the chassis appropriately movable. In the same way, any combination of the vehicle configurations 1, 3, 4 and 5 can be provided in one vehicle as can any combination of the vehicle configurations 1, 3, 4 and 6 and any combination of vehicle configurations 1, 3, 4, and 7.
